UNITED STATES PATENT OFFICE.

PHILIP S. DELANY, OF KANSAS CITY, MISSOURI, ASSIGNOR TO UNIVERSAL VENTILATING COMPANY, OF KANSAS CITY, MISSOURI, A CORPORATION OF MAINE.

VENTILATOR.

1,113,883.

Specification of Letters Patent. Patented Oct. 13, 1914.

Application filed August 19, 1912. Serial No. 715,897.

To all whom it may concern:

Be it known that I, PHILIP S. DELANY, a citizen of the United States, residing at Kansas City, in the county of Jackson and 5 State of Missouri, have invented certain new and useful Improvements in Ventilators; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to ventilators, and more particularly to a device of that type which is adapted for confinement within an opening in a window sash, the principal object of the present invention being to provide a ventilator of this type having an adjustable door member for regulating the air intake and having screens for filtering the air during its passage through the ventilator. In accomplishing this object, I have 20 provided the improved details of structure hereinafter described and illustrated in the accompanying drawings, wherein:—

Figure I is a perspective view of a window sash equipped with a ventilator constructed 25 according to my invention. Fig. II is an enlarged cross-section of the sash and ventilator. Fig. III is a detail perspective view of the outside ventilator box. Fig. IV is a similar view of the inside box. Fig. V is a 30 vertical section of the sash on the line V—V, Fig. II. Fig. VI is a similar view on the same line, but looking in the opposite direction to show the front box from the rear. Fig. VII is a detail view of part of the 35 back box showing the screen lip. Fig. VIII is a similar view of the front box showing the clip for the front screen.

Referring more in detail to the parts: 1 designates a window sash having an opening 2 extending longitudinally therein. Extending into the opening 2 from the outside 45 of the sash is a box 3 having an opening 4 extending longitudinally in its lower portion and having closed ends 5, the inner edge 50 of the upper portion of the box having a depending lip 6 forming a trap 7 for the rear screen, and the lower end of the box having vertical corrugations 3' through 55 which the ventilator may be drained, when drainage is required. Rising from the

lower edge of the box is a curved deflector 8 which terminates about the center of the box, and has a back-turned lip 9 which is slit at intervals throughout its length to provide lips 10 which are curved forwardly 60 and perform the function of spring clips for supporting the rear screen and holding same in place. The rear screen comprises a frame 11 which is adapted to project through the opening between the upper box lip 6 and the 65 forward edge of the deflector 8, so that when its upper edge is in the corner of the box, its lower edge can be sprung over the clips 10 to seat on the back-turned lip 9 and on said clips. 70

Seated in the front of the opening 2 is a box 12 having an opening 13 throughout substantially its entire length and width, the lower edge of the box being slit to form the lips 14 which are turned forwardly and up-curved to support a front screen 15. The inner edges of the box at the ends of the opening are also slit and turned back to form the lips 16, for engaging the ends of the screen when the latter is projected into the 80 box. Between the lips 16 and the ends of the box are vertical slots 17 through which the friction latch plates on the front door are projected, as will presently be described. 75

The box 12 is held within the sash opening by a collar 18 having horizontal flanges 19 overlaying the inner faces of the box 12, and vertical flanges 20 which project over the face of the sash at the edges of the opening 2, the exposed flanges being provided 85 with apertures through which screws, or the like, may be projected into the sash to hold the collar in place. The upper horizontal flange 19 of the collar is slit in line with the lips 14, and turned downwardly to form the upper spring clips 90 22 for holding the upper edge of the front screen. As the front screen is held in place by the lips 14 and 16 and clips 22, past which the screen is projected to 100 gain its seat, I provide the screen with finger holds 23, preferably constructed as lips, formed integral with and projecting inwardly from the ends of the screen rim in front of but spaced from the screen, so that 105 a person wishing to insert or remove the screen may grip the finger holds and thereby easily handle the screen.

Fixed in the ends of the collar 20 at the lower front portion thereof is a rod 24, and 110

revolvably mounted on said rod is a sleeve 26 which carries a front door 26 preferably formed of sheet metal and adapted to completely close the box 20, the upper edge of the plate being provided with a rail 27 which may overlie the upper edge of the box and serve as a stop to limit the inward travel thereof. Fixed to the inner face of the door adjacent the ends thereof are the latch plates 28, which are substantially triangular in shape and adapted for projection into and travel through the slots 17 at the ends of the inner box 12. Near the edge of each plate 28 is a strip 29 which is separated from the body of the plate by a slot 29' and has outwardly projecting corrugations 30 adapted to wipe the inner faces of the ends of the keeper collar, so that they will frictionally hold the door at any adjusted position, the plates projecting between the ends of the door box 3 and the ends of the sash opening when the door is closed. I also prefer to provide the door 26 with a damper plate 31 which may be manipulated by a knob 32 which projects through the door to the outer face thereof.

In using the device, the inner and outer boxes are fixed in place, the inner box being held in position by its collar and the outer screen is projected through the inner box and seated in its trap by projecting the outer end into the upper corner of the box 3, and by pushing the lower end over the spring clips 10, so that it may gain its seat and be yieldingly held in place therein. The inner screen is then projected through the inner face of the opening and pushed past the lips 14 and 16 and spring clips 22 to gain its seat over the opening in the inner box. The front door may then be inclined to regulate the amount of draft therethrough and deflect the air upwardly into a room, or the door may be entirely closed and the intake of air regulated by means of the damper. By having the outer screen set at an incline above the stationary deflector, dust thrown upwardly by the stationary member will be deflected against the back of the trap and fall back through the opening in the rear box.

When the ventilator is to be cleaned, the inner screen may be removed by grasping the finger holds thereon and pulling the screen outwardly past the spring clips, the outer screen being also removable by pulling the inner end over the clips on the deflector and removing same through the inner box. It is apparent that should either of the screens be left out, the air may still be filtered by the other screen during its travel through the ventilator. It is also apparent that should a hard storm drive rain up through the outer box into the interior of the sash, it may drain through the 65 vertical corrugations 3'.

Having thus described my invention, what I claim as new therein and desire to secure by Letters-Patent, is:—

1. In a ventilator, the combination with a sash, having an opening therein, of separate boxes projected into said opening from inner and outer faces of the sash and each provided with a screen opening, a removable screen covering the opening in the inner box, and a removable screen covering the opening in the outer box and adapted for removal through the opening in the inner box.

2. In a ventilator, the combination with a sash, having an opening therein, of separate boxes projected into said opening from inner and outer faces of the sash and each provided with a screen opening, a removable screen covering the opening in the inner box, a removable screen covering the opening in the outer box and adapted for removal through the opening in the inner box, and means on said boxes for yieldingly holding the screens in place.

3. The combination with a sash having an opening therein, of a box projected into said opening from the outer face of the sash, and having a closed upper portion and open lower portion, an upwardly and inwardly curved deflector projecting into the box from the bottom of the open lower portion thereof, and a screen supported on the upper edge of the deflector and bearing against the upper portion of the box.

4. The combination with a sash having an opening therein, of a box projected into the opening from the outer face of the sash and comprising an open lower portion having an inwardly and upwardly curved deflector entering the box from the bottom of said opening, and having inwardly and outwardly extended lips on its upper edge, the said box comprising a closed upper portion having a flange within the sash above the inner edge of the deflector forming a restricted opening, and a screen adapted for projection through the restricted opening and supported in an inclined position by the lips on the deflector and outer closed portion of the box.

5. In a ventilator, the combination with a sash having an opening therein, of a box in the outer portion of said opening having a lower mouth and an inwardly and upwardly curved deflector, the upper portion of said deflector having an outwardly facing lip and inwardly facing clips, and a screen supported on said lip and yieldingly held by said clips, substantially as set forth.

6. In a ventilator, the combination with a sash having an opening therein, of a box located within said opening and comprising an inwardly and upwardly curved deflector having oppositely directed lip and portions on its upper edge, and having a flange

depending over said lip, and a screen extending at an incline through the upper portion of the box with its lower edge supported by said lip and yieldingly held in place by said clips.

7. In a ventilator, the combination with a sash having an opening therein, of a box seated in said opening and having an inner and upper screen aperture, and a lower and outer intake port, the edges of the box facing said aperture being slit and bent to form

10 supporting and keeper lips, and a screen seated on the supporting lips and yieldingly held in place by the keeper lips, substantially as set forth.

8. In a ventilator, the combination with a sash having an opening therein, of a box located within said opening and having a screen aperture, the box at the edges of the 20 aperture being slit and turned outwardly to form keeper lips, a collar inclosing the edges of said box and having backwardly turned clips, a screen adapted to seat on lower box lips and to push past the collar 25 clips to cover said aperture, and inwardly turned finger holds on the ends of said screen, substantially as set forth.

9. In a ventilator, the combination with a sash having an opening therein, of a box 30 located within the opening and having vertical slots at its ends, a door hingedly connected with the box, and latch plates fixed on said door and adapted for travel within the end slots.

35 10. In a ventilator, the combination with a sash having an opening therein, of an outer box located within but spaced from

the ends of the opening, an inner box fixed within the opening and having vertical slots, a door hinged to said inner box, and latch plates on the ends of said door adapted for travel within the slots and between the ends of the outer box and sash, substantially as set forth.

11. In a ventilator, the combination with a sash having an opening therein, of a box located within the opening, a door hingedly connected with the box, and a friction latch on said door comprising a plate having corrugations adapted to wipe the end of the 50 box, substantially as set forth.

12. In a ventilator, the combination with a sash having an opening therein, of a box located within the opening and provided with vertical slots, a door hingedly connected with the box, and plates fixed to the ends of the door and adapted for travel in said slots, said plates having corrugations adapted for wiping the ends of the box, for the purpose set forth.

13. In a ventilator, the combination with a sash having an opening therein, of a box located within the opening, a door, and latch plates on the ends of the door, said plates being slotted to form relatively flexible straps, and said straps being provided with transverse corrugations, for the purpose set forth.

In testimony whereof I affix my signature in presence of two witnesses.

PHILIP S. DELANY.
